Attorney

UNITED STATES PATENT OFFICE.

HARVEY JENKINS, OF GOTHENBURG, NEBRASKA.

CLOTHESPIN.

Application filed June 12, 1923. Serial No. 644,982.

To all whom it may concern:

Be it known that I, HARVEY JENKINS, a citizen of the United States, residing at Gothenburg, in the county of Dawson and 5 State of Nebraska, have invented certain new and useful Improvements in Clothespins, of which the following is a specification.

The present invention relates to a clothes 10 pin and has for its principal object to generally improve upon devices of this nature by providing a simple and efficient structure, one which is reliable in use, inexpensive to manufacture, durable, and well 15 adapted to the purpose for which it is designed.

Another important object of the invention 20 is to provide a clothes pin formed from a single strand of resilient wire which is bent so as to provide a structure which will efficiently hold clothes upon a line without any danger of injuring the clothes and constructed so that it may be easily engaged 25 with and disengaged from the clothes and line.

With the above and numerous other objects in view as will appear as the description progresses, the invention resides in 30 certain novel features of construction and in the arrangement of parts as will be hereinafter more fully described.

In the drawing:

Figure 1 is a front elevation of the clothes 35 pin showing the same in use;

Figure 2 is an edge elevation thereof;

Figure 3 is an edge detail perspective thereof.

Referring to the drawing in detail it will 40 be seen that the clothes pin is formed from a single strand of wire of a resilient nature which strand of wire is bent so as to provide a substantially U-shaped body portion 1 the intermediate portion 2 of which is bent out of alignment with legs 3 as is disclosed to 45 advantage in Figure 2. The upper end of one leg 3 is bent inwardly and terminates in an eye 4. The other leg 3 has its upward end bent inwardly through the eye and extended downwardly between the two 50 legs to form an arm 5. This arm 5 includes a straight portion 7 and another straight portion 8 which is angularly disposed thereto, preferably at an obtuse angle. The end

of portion 8 terminates in an eye or loop 9 which is curved outwardly from the body. 55

From the above description it will be seen that because of the loop 9 and the offset relation of the intermediate portion 2 to the legs 3 of the body 1 that the clothes pin may be readily slipped over the line and the 60 clothing thereon be securely held in place against removal by the wind or in any other undesirable or unauthorized manner. It will also be seen that the clothes pin may be 65 equally pulled from engagement with the line when desired and that there will be no danger whatsoever of tearing the clothing as the pin is being engaged with the line or removed therefrom.

I have, in the present instance, shown 70 and described the preferred embodiment of the clothes pin which will give in practice satisfaction and reliable results, and it is to be understood that the same is susceptible of modifications in various particulars without departing from the spirit or scope of the invention or sacrificing any of its advantages. 75

Having thus described my invention, what I claim as new is:

A clothes pin of the class described formed 80 from a single strand of resilient wire bent to provide a U-shaped body including an intermediate portion and two parallel spaced legs, the intermediate portion being curved 85 out of alignment with the plane in which the major portions of the legs are disposed, one of said legs having its end bent inwardly and terminating in an eye, the other leg having its end bent inwardly and extending 90 through the eye and terminating in an arm disposed approximately between the legs of the U-shaped body and including two straight portions angularly disposed in relation to each other and terminating in a 95 coil adjacent the intermediate portion of the body, said intermediate portion of the body diverging from that straight portion of the arm which is provided with the coil.

In testimony whereof I affix my signature in presence of two witnesses.

HARVEY JENKINS.
